UNITED STATES PATENT OFFICE

2,634,347

CIRCUIT BREAKER

Morgan J. Lewis, Philadelphia, Pa.

Original application October 17, 1947, Serial No. 780,553, now Patent No. 2,620,417, dated December 2, 1952. Divided and this application November 6, 1951, Serial No. 255,000

1 Claim. (Cl. 200—88)

1

My invention relates to electric contact making and breaking devices, particularly of the character which provide automatic quick release in case of overload or short circuit, and are commonly known as circuit breakers.

A purpose of the invention is to make the interconnecting parts for releasing and restoring the breaker more reliable and inexpensive in construction.

A further purpose is to guide the end of the toggle breaking arm remote from the pivot of the releasing plate as later explained.

A further purpose is to guide the automatic releasing arm of the releasing plate.

Further purposes appear in the specification and in the claim.

In the drawings I have chosen to illustrate one only of the numerous embodiments in which my invention may appear, choosing the forms shown from the standpoints of convenience in illustration, satisfactory operation and clear demonstration of the principles involved.

Figure 1 is a fragmentary top plan view of my improved circuit breaker, eliminating the housing.

Figure 2 is a section of Figure 1 on the line 2—2, breaking away one end of the outer housing.

Figure 3 is a section corresponding to Figure 2 showing only the switch in the position at which release begins.

Figure 4 is a view corresponding to Figure 3 showing the switch fully open.

Figure 5 is an exploded fragmentary perspective showing the toggle and contacts.

Figure 6 is an enlarged detail longitudinal section through the movable contacts.

Figures 7, 8 and 9 are diagrammatic enlarged side elevations showing the steps in closing the contacts.

Figure 10 is a sectional perspective of the release mechanism.

Figure 11 is a perspective of the main supporting bracket.

Figure 12 is a detail perspective of the thermostatic elements and magnetic armature.

Describing in illustration but not in limitation and referring to the drawings:

The present application is a division of my U. S. patent application, Serial No. 780,553, filed October 17, 1947, for Circuit Breaker which has become U. S. Patent No. 2,620,417, issued December 2, 1952.

The present subject matter is a further development of my U. S. Patent No. 1,888,559, dated November 22, 1932, for Electric Switch. Insofar

as the construction and operation of the present device is the same as that of my prior patent, I will describe it generally and refer those interested to my patent for further details.

In the prior art, on a dead short circuit or other similar condition circuit breakers for example of the type of my Patent No. 1,888,559 have in some cases suffered serious damage, due to the fact that the current was not reduced rapidly enough during the first part of the opening movement of the contacts, so that damage was in some cases done to the circuit breaker itself. This condition was in part due to the character of contacts used in the prior art device, and the fact that during the opening of the breaker the current was not cut down sufficiently rapidly when the contacts were just beginning to open, partly open or just completely open.

The damage caused to the breaker in some cases took the form of burning out the thermostatic elements or alternatively of burning out the electromagnetic coils or both. While these injuries to the breaker could of course be repaired they did place the equipment out of service until a repair was completed and were very annoying.

The present invention represents an improvement over the prior art in avoiding this difficulty by assuring that even on a dead short circuit the reduction in current through the breaker will be so rapid that not only will the breaker protect the load and the generation system, but it will of course adequately protect itself. The present invention, therefore, is especially well suited to provide protection of electromagnetic and thermostatic elements of a breaker during the opening of the breaker.

The switch of the present invention comprises an outer metallic housing 20 of general box formation, which is closed at the top by an outer cover 21 suitably fastened thereto, as by screws and seals ordinarily used in electrical work (not shown), and outwardly deformed at 22 to permit motion of the switch. Within the housing 20 and suitably bolted at 23 to the rear or bottom thereof, I provide an insulating base 24, preferably of electrical porcelain or the like. At one end the base is formed to provide a terminal block 25 with suitable separating ribs 26 spacing terminals 27 connected to the line, and terminals 28 connected to the load. The ribs 26 terminate short of ribs 30 for mounting the switch, leaving a space 31 extending across the base and engaging and locking the lower end of an insulating end wall 32 (Figure 2) of an inner cover 33 which encloses the switch proper while permitting ac-

cess to the terminal block. The upper and suitably metallic portion 34 of the inner cover is joined to the insulating end wall 32 as by rivets 32', shrouded by washers 32" of rubber or the like. The inner cover is deformed at 34' to fit within deformed portion 22 on the outer cover.

It will thus be evident that the inner cover 33 is suitably secured (as by screws and seals not shown) and prevents unauthorized access to the switch while nevertheless permitting access to the terminal block for connection or disconnection.

The switch proper is mounted on a channel-shaped bracket 34 suitably fastened to the insulating base at 35 and insulated from the electrical parts (the bracket is seen more in detail in Figure 11). The bracket has a suitable base 36, side walls 37 and a cover 38 having projections 40 for protecting the biasing spring later to be described, and guiding the upper ends of the releasing plates. At the end remote from the switch there is also a tongue 41 for protecting another biasing spring.

From the bracket, operating mechanism manipulates switch blades 42 and 43 pivoted at 44 on conducting standards 45. The standards are suitably mounted on the insulating base and interconnected to the load through thermostat supports 46 mounted on the base, metallic thermostatic strips 47 vertically supported thereon near the bottoms of the strips, then through downwardly extending metallic thermostatic strips 48 joined at the top to strips 47, through support 50 on which the strip 48 is mounted, through magnet coil 51 and then through terminal strip 28.

The thermostatic strips 47 and 48 are positioned so as to move toward the magnet coils with increased temperatures as later explained.

The switch blades 42 and 43 are interconnected by an insulating bar 52 extending from side to side toward the outer ends and suitably fastened to the switch blades as at 53 (Figure 5).

The cooperating fixed contacts comprise elongated strips 54 of copper or the like suitably mounted on the base and interconnected with the line by bus bars 55, preferably carried in recesses beneath the base. Each of the fixed contacts is generally bent away from the base at 56 and above this point is inclined with respect to the base and with respect to an imaginary line between the switch pivot 44 and any point on the fixed contact. Thus there is in the form shown an outer, less steeply inclined portion 57, near the end of the fixed contact remote from the pivot of the switch blade, and an intermediate more steeply inclined portion 58 as best seen in Figures 7, 8 and 9.

On the outer end of each switch blade is a movable contact 63 electrically connected to the blade as by an electrically conducting spacer 61 screwed to the blade at 62 and riveted to the contact at 63 (Figure 6). Rotation is prevented by notch 62' engaging the blade.

The movable contact is specially constructed so as to prevent fouling. With this object it is constructed of a number of separate contact pads preferably in the form of resilient strips of spring material such as spring bronze, spring brass or beryllium copper, with or without contact blocks. The pads are preferably arranged as overlapping leaves so that they will contact the fixed contact at a plurality of points and preferably successively. The forwardmost pad as shown is made up of two leaves 64 and 65 mounting a metallic contact block 66 at the outer ends, and in closing the

switch making contact with the outer extremity of the fixed contact 54 before any other contact pad has made contact. Thus if any arcing is likely to take place, on the making or on the breaking, it will take place in the region 67 of Figure 7, since in this position no other portion of the contact pads will be closely adjacent to the fixed contact. Thus arcing and pitting over the portion 58 of the fixed contact is prevented.

The successive contact in closing and the successive breaking in opening will be accomplished by other contact pads, suitably the pad 68 which is next to make contact in closing as shown by Figure 8, backed up by the pad above at 70. An instant after contact is made by the pad 68, contact is made by the next pad 71 which is somewhat shorter, and finally contact is made by the last pad 72. The pads 68, 70 and 71 suitably have reverse bends on their outer ends to increase the current carrying capacity slightly. Of course any suitable number of contact pads arranged in echelon may be used.

It will be evident, therefore, that in closing the contacts of each switch blade, contact will first be made by the outermost pad and then successively by the pads whose outer ends are nearer to the pivot, whereas in opening the reverse will take place, and the pads whose outer ends are nearer to the pivot will break contact while current is still flowing through the outermost pad and therefore while there is little or no tendency to arc and spoil the contact surface at 58.

Whereas in the present invention any suitable number of switch poles may be used, I have illustrated in this case a two pole switch, but it will be understood that the invention is in no way restricted to a switch of this type.

Each of the fixed contacts is surrounded on both sides by an arcing shoe 73, suitably of steel, which is preferably a U-shaped member having a base 74, upstanding sides 75, flaring outer ends 76 and inclined outer edges 77 which conform generally to the slope of the fixed contact at 57 and 58. It will thus be evident that as the movable contacts separate they are laterally within arcing distance of the arcing shoes at each side, whereas the fixed contact is likewise at each side within arcing distance of the arcing shoes. The arcing shoes are, however, preferably electrically connected to the fixed contacts, and therefore it will be evident that the arcing will primarily be between the movable contact and the arcing shoes, and will be finally broken by the outwardly flaring edges of the shoes. It is important to note, however, that the inclined character of the outer edges of the shoes tends to space the contact pads substantially widely from the arcing shoes as the movable contact moves outwardly, but the contact block 66 is made slightly wider as shown in Figures 1 and 5, so that most of the arcing will take place on the contact block, protecting the sides of the contact pads.

The operation of the switch is accomplished preferably by a crank handle 78 which is pivotally mounted at 80 on the housing and extends outside the housing to provide a suitable handle for operation. The crank 78 is biased toward the switch closing position by a torsion spring 81, one end of which engages the housing. Throughout the portion of the crank which contacts the operating parts it is surrounded by insulating sleeve 82. The crank extends through an elongated slot 83 of a channel-shaped toggle member 84 which makes toggle pivotal connection at 85 with a channel-shaped forward toggle

member 86 which has pivotal connection at 87 with a longitudinal slot 88 of a saddle 90 mounted near the middle on the insulating cross connection 52 of the switch. The toggle is spring urged toward straightening by a torsion spring 91 suitably surrounding the pivot 85.

To sustain the pressure in closing the switch and avoid breaking through the insulation 82, a socket 92 is provided at the end of slot 83 toward the fixed contacts.

The switch blades are biased toward opening by a tension spring 93 connecting from a spring abutment 94 on the bracket 34 to a spring engaging hook 95 on the insulating bar 52.

The switch is secured in closed position by a latch 96 (one for each pole) pivotally mounted at 97 on the bracket and spring urged toward latching position by a compression spring 98 engaging a lever end 100 near the base of the latch. The latch is limited against moving rearwardly beyond its latching position through engagement of projections 101 with the base of the bracket.

The switch may be opened manually by pulling on the handle in such a way as to operate the crank 89 counterclockwise in Figure 2, pulling on the toggle and moving the pivot 87 in the slot 88 toward the switch blade pivot so as to withdraw the pivot 87 from engagement beneath the latch 96 as in my patent above referred to.

The switch may likewise be manually closed by moving the handle in the direction to swing the crank clockwise in Figure 2, forcing the movable contacts into clamping engagement with the fixed contacts, forcing the pivot 87 forward in the slot 88 and permitting it to deflect the latch 96 and be held beneath the latch as shown in Figure 2.

Automatic release of the latch 96 is accomplished by a releasing plate 102 as best seen in Figure 10. One releasing plate is provided for each switch blade, and the releasing plate is conveniently pivoted at 97 on the latch pivot, suitably on the inside of the corresponding latch, the releasing plates being separated by a spacer 103 (Figure 10). Each releasing plate has a latch releasing arm 104 extending away from the base and adapted to engage a cross connection 105 between the latches, which, with a top cross connection 106, assures that the latches move together. The releasing plate also has a longitudinal extending body 107 (Figure 10) from which projects away from the base a toggle breaking arm 108, adapted to engage the toggle pivot 85. Also at the rearward end is the automatic releasing arm 110 which projects outwardly through an opening in the bracket to engage under an automatic releasing dog 111 (best seen in Figure 10) which is mounted on the thermostatic arms 47 and 48 in the position opposite to the coil 51. The upper joining ends of the thermostatic arms 47 and 48 are preferably insulated on either side at 112 and 113 to permit mounting the dog 110 without connecting it into the electrical circuit.

On the side of the upper ends of the thermostatic arms 47 and 48 toward the coil is mounted an armature 114 of suitable magnetic susceptible material, such as low carbon steel. In the prior art when an unbroken disc armature was employed, considerable difficulty was encountered with alternating current hum when the overload approached a condition close to that for kicking out the circuit breaker. I have discovered that this difficulty may be overcome by inserting an

air gap or slot 115 extending radially through the armature from the outer circumference to a point adjacent to the interior as best seen in Figure 12. It has been found that by employing the slot described it is possible to maintain sharp overload release and nevertheless operate without objectionable noise for long periods at overloads slightly below the release point. The coils 51 are provided with suitable cores and pole pieces 116 to cooperate with the armature.

The toggle breaking projection 108 of the releasing plate may be conveniently guided by the side of one of the protecting prongs 40 as seen at 117, and the base of the automatic releasing arm 110 is suitably guided by the side of the tongue 41 at 118 (Figure 10). Each releasing plate is biased toward release position by a tension spring 120 extending from the abutment 94 to a spring anchor 121 on the rearward edge of each releasing plate.

In operation the switch of the present invention will frequently be used to replace the main fuses on a 110 volt alternating or direct current supply to a house, or the like, although of course it may be used in numerous other applications, as for example, to provide a circuit breaker for motors or other load equipment at any suitable voltage.

The device can be opened and closed like an ordinary switch to turn the current off or on manually simply by operating the handle. The toggle will remain stiff and the contacts will be forced closed, first bringing the contact blocks 66 into engagement with the portions 57 of the fixed contacts and then successively bringing the individual resilient metallic contact pads into engagement with the portions 58. In breaking the circuit the reverse sequence will be followed, the contact at each block 66 being the last broken, and the arcing shoes having diverging edges terminating on an incline similar to that of the fixed contacts and that of the movable contacts at that position, breaking the arc.

When the device is closed automatic operation will begin, since the current will pass through the thermostatic arms 47 and 48 which are biased toward opening of the automatic release by moving the release dog 111 away from engagement with the automatic releasing arm 110 (Figure 10), thus protecting against long continued overloads slightly above the proper value, and also because the current is flowing through coil 51, which by pulling on the armature 114 is tending to pull the automatic release dog 110 out from engagement with the arm 110. There is enough time lag to prevent release on a momentary somewhat excessive current flow incident to starting a motor or the like.

The thermostatic arms are not used to open the switch but to keep the coils from opening the switch on momentary overloads such as starting motors. The heavier the overload or short, the more the coil is effective and the less the thermostatic arms are effective, so that as the thermostatic arms heat up they move the armature nearer to the coil.

Should an excessive overload or a short circuit occur, the automatic release dog 111 will move out from engagement with the automatic releasing arm 110 and the corresponding releasing plate 102 will swing pivotally under the action of its biasing spring 120. This will cause the arm 104 to move the latch 96 to unlatching position and will cause the toggle breaking projection 108 to break the toggle as shown in Fig-

ure 3, causing the switch to open under the action of the switch biasing spring 93 as shown in Figure 4. As the switch opens its movable contacts break in the order referred to and the arcing shoes break the arc.

The switch is now reset manually, after repairing the difficulty in the circuit, by moving the handle in the direction to pull the crank counterclockwise in Figures 2, 3 and 4, so that the toggle breaking projection 108 is engaged at 122 with the anchorage 90 on the insulating cross bar 52. This engagement is shown in Figure 4, although the crank is no longer in the limited counterclockwise position. This restores the releasing plate to its engagement with the automatic release dog as shown in Figure 10, prepared for further automatic release. The switch handle is then moved in the opposite direction to carry the toggle forward and close the switch as in the previously described manual operation, restoring the condition shown in Figure 2. Should the device nevertheless encounter a further short circuit or excessive overload when it is manually closed, it will kick out notwithstanding the pressure on the handle due to the breaking of the toggle and the release of the latch.

An important function of the special contacts and arcing horns in accordance with the invention is that the thermostatic elements and/or electromagnets of the breaker are adequately protected against damage during the opening, due to the fact that the current incident to a short circuit or other greatly abnormal current flow is cut off too rapidly to do permanent damage.

It will be evident of course that the present invention finds its best expression in circuit breakers, but it also may be applied to great advantage in switch mechanism of other types.

In view of my invention and disclosure variations and modifications to meet individual whim or particular need will doubtless become evident to others skilled in the art, to obtain all or part of the benefits of my invention without copying the structure shown, and I, therefore, claim all such inssofar as they fall within the reasonable spirit and scope of my claim.

Having thus described my invention what I claim as new and desire to secure by Letters Patent is:

In a circuit breaker, a channel-shaped bracket, a latch pivoted on the forward end of the bracket, spring means to urge the latch toward latching position, a movable switch blade, a pivot for the movable switch blade, spring means for biasing the movable switch blade toward opening, a movable contact on the end of the movable switch blade, a fixed contact cooperating with the movable contact, a toggle for closing the switch blade, an automatic releasing dog adjacent the rearward end of the bracket, 15 thermostatic arms supporting the automatic releasing dog and tending to move it toward opening position as they become more heated, an armature mounted with the automatic releasing dog, an electromagnet urging the armature toward the release position of the automatic releasing dog and a releasing plate pivoted on the forward end of the bracket, spring urged toward opening position, having a releasing arm which operates the latch in opening, having 20 a toggle breaking projection which breaks the toggle in opening, having a return abutment for engaging a part movable with the switch blade for restoring to automatic release position and having an automatic releasing arm for retention by the automatic releasing dog, in combination with a projection on the bracket guiding the end of the toggle breaking arm remote from the pivot of the releasing plate and a tongue on the bracket guiding the automatic releasing arm of the releasing plate.
